UNITED STATES PATENT OFFICE.

GUSTAVE THIBAULT, OF WHITEHALL, NEW YORK.

DESIGN FOR A ROSARY.

59,306.

Specification for Design.

Patented Oct. 4, 1921.

Application filed July 19, 1921. Serial No. 485,970. Term of patent 14 years.

To all whom it may concern:

Be it known that I, GUSTAVE THIBAULT, a citizen of the United States, and a resident of Whitehall, in the county of Washington and State of New York, have invented a new, original, and ornamental Design for Rosaries, of which the following is a specification, reference being had to the accompanying drawing, forming part thereof.

Figure 1 is a plan view showing my new design for a rosary; and

Fig. 2 is a view in transverse section through one of the Gloria Patri beads on the line 2—2 of Fig. 1.

I claim:

The ornamental design for a rosary, as shown.

GUSTAVE THIBAULT.
